IGNITION APPARATUS

Jakob R. Frei, Sidney, N. Y., assignor to Bendix
Aviation Corporation, New York, N. Y., a cor-
poration of Delaware

Application October 15, 1942, Serial No. 462,127

16 Claims. (Cl. 171—209)

1 This invention relates to ignition apparatus and more particularly to supercharged ignition devices and pump means therefor.

One of the objects of the invention is to provide a novel magneto-generator embodying pump means for maintaining the air in the interior thereof under pressure.

Another object is to provide an ignition apparatus having a novel arrangement of elements whereby said apparatus is supercharged.

A further object is to provide a novel magneto-generator having a distributor compartment and means drivably connected to the main rotor shaft for supercharging said compartment.

Still another object is to provide a novel pump apparatus adapted to be operatively mounted and assembled in a novel manner relative to the drive means therefor so as to eliminate any possibility of binding of the movable pumping members and so as to maintain efficiency losses due to leakage during compression at a minimum.

A still further object is to provide ignition apparatus having a supercharged chamber and a high tension conductor leading into said chamber and novel means whereby arcing from said conductor is minimized and said conductor and its terminal are kept dry.

Still another object is to provide a compact and efficient pump apparatus combined in a novel manner with the main rotor shaft of a magneto whereby air under pressure may be delivered to any portion of the interior of said magneto.

The above and further objects and novel features of the invention will more fully appear from the following detailed description when the same is read in connection with the accompanying drawings. It is to be expressly understood, however, that the drawings are for the purpose of illustration only and are not intended to define the limits of the invention, reference for this latter purpose being had primarily to the appended claims.

In the drawings, wherein like reference characters refer to like parts throughout the several views,

Fig. 1 is an elevation view, with parts broken away and with parts shown in section, of a magneto-generator embodying one form of the present invention;

Fig. 2 is a sectional view, with parts broken away, taken substantially along line 2—2 of Fig. 1 and showing apparatus suitable for effecting the admission and discharge of air to and from the supercharger pump;

2 Fig. 3 is a sectional view, with parts broken away, taken substantially along line 3—3 of Fig. 1 and showing the supercharger construction;

Fig. 4 is an enlarged fragmentary view of a portion of a magneto similar to that shown in Fig. 1 having a modified form of pump apparatus operatively mounted therein;

Fig. 5 is a sectional view, with parts broken away, taken substantially along line 5—5 of Fig. 10, 4; and

Fig. 6 is a similar view taken substantially along line 6—6 of Fig. 4.

Referring to Figs. 1 to 3, the invention is illustrated, by way of example, as embodied in a magneto-generator of a type generally similar in construction to that shown in the Walter J. Spengler Patent No. 2,104,140 of January 4, 1938, for "Magneto generator." The magneto-generator in the form illustrated is provided with a housing 10 comprising a pair of longitudinally spaced main sections 10a and 10b secured end to end. A front cover member 11 is mounted on the outer end of section 10a and cooperates with side wall 12 of the latter to form a compartment 11a for receiving a suitable gear drive to be more fully described hereinafter. Mounted in the lower end of housing 10 so as to extend longitudinally therethrough is a main rotor shaft 13 which is suitably journaled for rotation in bearing means carried by said housing. The bearing means preferably comprise a pair of ball bearings 14 provided adjacent to the shaft ends, one of said bearings being shown in Fig. 1 mounted in wall 12 and the other (not shown) being suitably supported in housing section 10b. The forward end of said shaft projects through chamber 11a and cover member 11 and has a suitable driving member, such as a gear 15, mounted thereon, which gear may be drivably connected to the crank-shaft of an internal combustion engine.

Secured to rotor shaft 13 for rotation therewith is a multiple pole magnetic rotor 16 which cooperates in a manner well understood in the art with a pair of stationary laminated pole pieces 17, only portions of which are shown, and an ignition coil 18, the latter being supported above said rotor by said pole pieces and covered by a strapped-on housing section 10c. Connected to the high tension winding of said coil is a spring pressed terminal 19 which constitutes an element of a current conducting connector 20, the latter being mounted in a distributor block 21 to constitute the central electrode thereof. The distributor block, in the form illustrated, is secured

between housing sections 10a and 10c to form the right-hand wall, as viewed in Fig. 1, of a distributor chamber 22. A gasket 23 is preferably interposed between the engaging portions of said distributor block and said housing section to render the connection between the latter fluid-tight.

Mounted in chamber 22 for cooperation with block 21 is a rotatable distributor element or finger 24 which carries a central or axial contact 25 adapted to be in continuous brushing engagement with electrode 20 during rotation of said finger. A peripheral contact 26 mounted in the outer end of said finger connects electrically with contact 25 and is adapted to successively cooperate in a well known manner with a plurality of 10 annularly disposed contacts 27 carried by block 21. In order to rotate finger 24, a distributor rotor 28 extends through wall 12 and is journaled in said wall by suitable bearings 29. The inner end of said rotor is provided with a flange 30 to which said finger is rigidly secured and the outer end thereof projects into compartment 11a. An inwardly extending flange or sleeve 31 is formed with wall 12 to surround rotor 28 and serves as a 20 socket for a suitable fluid seal 32 which has the inner periphery thereof engaging a sleeve 33 mounted on said rotor, said sleeve being in fluid-tight engagement with the latter. A passage 34 is preferably provided in wall 12 to connect the space between the outer wall of said seal and bearings 29 with chamber 11a and thereby prevent a back pressure from being built up in said space which would tend to prevent proper lubricating 30 of the bearings.

Distributor rotor 28 is preferably driven by a 35 gear drive contained in compartment 11a, which drive comprises a gear 37 rigidly secured to said rotor by suitable means, such as a screw 38 and a key 39. Gear 37 is in mesh with a pinion 40 which is splined to magneto rotor shaft 13 so that the rotary distributor member is driven in 40 timed relation with the magneto rotor.

In order to supercharge the interior of distributor chamber 22 and thereby better adapt the apparatus for operation at high altitudes, novel 45 pump means are provided and are arranged in a novel manner in housing 10. As shown, said pump means comprise a housing 41 eccentrically mounted around shaft 13 and rigidly secured to housing 10 adjacent magnetic rotor 18 in a novel manner, more fully described hereinafter. Housing 41 preferably includes a cylindrical wall member 41a and side wall plates or members 41b which are provided with recesses for shaft 13, said recesses being bordered by outwardly extending flanges or sleeves 41c formed with said side wall members. Sleeves 41c serve to mount a 50 pair of bushings 42 which are in engagement with said shaft and have radial flanges 42a formed therewith, said flanges being mounted in indentations provided therefor in side walls 41b so that the inner end of each of bushings 42 extends slightly beyond the inner face of a side wall member 41b in which said bushing is carried so as to maintain a proper operating clearance between the ends of a rotor 43, which may move axially of shaft 13, and side walls 41b. Cylindrical pump rotor 43 is concentric with respect to shaft 13 and is keyed or otherwise secured to the latter for rotation therewith and axial movement relative thereto. The radius of rotor 43 measured from the axis of rotation of shaft 13 is preferably almost equal to the shortest distance separating the inner periphery of the eccentrically disposed cylindrical casing member 41a and said axis so that

5 said rotor is substantially tangent to the inner surface of said wall at one point in the circumference thereof (Fig. 3).

To form a plurality of compression chambers in housing 41, a plurality of vanes or blades 44 (Fig. 3) are slidably mounted in radial slots 45 provided in rotor 43, said slots being preferably equally spaced around the periphery of said rotor and being at least as deep as the radial length of said vanes. The latter have the side edges thereof engaging side wall members 41b of the housing and during operation of said rotor have the outer edges centrifugally pressed into fluid-tight engagement with circumferential wall 41a of the housing. These outer vane edges are preferably blade or wedge-shaped to effect a better over-all fluid-tight engagement with said circumferential wall. During rotation of rotor 43, each successive pair of vanes 44 together with housing 41 and rotor 42 define a fluid-tight peripheral pressure or compression chamber wherein a volume of fluid may be compressed during each rotor revolution. To admit air to each of said chambers, the left-hand side plate 41b, as viewed in Fig. 1, is provided with an arcuate inlet port 46 (Fig. 3) which preferably has the outer edge thereof adjoining the inner surface of wall member 41a and which, as shown, may subtend an angle of approximately 90°. Air is admitted to each of the chambers during the period that the chamber overlaps said inlet port and the latter is arranged so that admission is cut off shortly after the chamber has assumed its maximum volume. Thereafter, rotation of the rotor effects air compression and the compressed air is discharged from the chamber through an arcuate discharge port 47 which also adjoins the inner surface of casing member 41a but which subtends a relatively small angle. Port 47 is 50 preferably located so that air discharge from each compression chamber terminates just prior to air admission into said chamber. As shown, adjacent edges of ports 46 and 47 are disposed equal angular distances on opposite sides of the point of tangency between rotor 42 and housing wall 41a and said edges are spaced apart an angular distance slightly greater than the angular length of each compression chamber.

In order to connect inlet port 46 to the exterior of magneto housing 18 and to deliver the compressed air discharged through port 47 to the interior of distributor chamber 22, a U-shaped hollow adapter or housing 48 (Figs. 1 and 2) is mounted in the lower end of housing section 10c so as to partially surround shaft 13. If desired, said adapter may be cast as an integral part of casing member 10a. Ends 48a of said adapter terminate adjacent an arcuate flange 22a which constitutes the bottom wall of chamber 22 and the portions of said ends which project longitudinally beyond said flange are flared upwardly (Fig. 1) to arcuately lengthen the side of said adapter adjacent pump housing 41. The latter side of said adapter is formed by a cover plate 49 of yieldable material which engages the left-hand side wall member 41b (Fig. 1) of said pump housing and is provided with a pair of ports 50 and 51 which register with inlet port 46 and discharge port 47, respectively, in said side wall member. The interior of housing 48 is separated into two fluid-tight compartments 52 and 53 by a wall 48b, and port 50 opens into compartment 52 while port 51 opens into compartment 53. Compartment 52 is connected by a suitable fitting 70 54 to the atmosphere, said fitting preferably em-

bodying a screen or other filter for removing foreign matter from the air being admitted into said compartment. Compartment 53 connects with the interior of chamber 22 by means of a tubular member 55 (Fig. 2) which is press-fitted or otherwise secured in flange 22a and in the end 48a of housing 48.

Housing 41 and adapter 48 are rigidly secured in operative position in housing 10 by being pressed or clamped between housing sections 10a and 10b. As shown in Fig. 1, a shoulder 56 formed on the interior of section 10b bears against a spacer element 57 which engages the right-hand wall member 41b while adapter 48 engages wall 12, said adapter and pump housing being arranged so as to have the parts thereof fixed in operative position by the pressure exerted thereon by sections 10a and 10b when the latter are secured to each other by suitable means, such as stud bolts 57a.

Novel means are provided for lubricating the bearing surfaces of bushings 42 and shaft 13. In the form shown, liquid oil is confined in the hollow 13a of shaft 13 and is forced by centrifugal action through radially extending plugs 42b made of porous bronze or other suitable material. Oil may thus be supplied in suitable quantities to the bearing surfaces of bushings 42 and to the adjacent walls of the pump cylinder and rotor.

It is desirable to prevent the building up of excessive pressures in chamber 22 and to provide a continuous circulation of air therethrough. Accordingly, in the illustrated embodiment, a plurality of bleeder holes 58, preferably three in number (only one being shown in Fig. 1), are arranged in a novel manner to discharge air into the interior of housing sections 10b, 10c, said holes being located in distributor block 21 adjacent to connector 20 so as to eject air in the vicinity of high tension terminal 19. As a result, said terminal is kept dry and arcing from said terminal to the walls of casing 10 is substantially eliminated.

In operation, rotor shaft 13 is driven from the engine crankshaft and actuates magnetic rotor 16 and distributor element 24 to generate and distribute high tension current to the spark plugs of the engine ignition system. Rotation of shaft 13 also actuates pump 41, 43 and supercharges distributor chamber 22. Air is admitted to compartment 52 of adapter 48 through fitting 54, being filtered by the latter, and passes through overlapping or registering ports 50 and 46 into one of the compression chambers formed in the pump by vanes 44, the latter being centrifugally pressed into fluid-tight engagement with peripheral housing wall 41a. During operation of rotor 43, the volume of each of the compression chambers is varied due to the eccentricity of housing 41 whereby the air in said chamber is compressed. The compressed air is discharged from each of said chambers through ports 47 and 51, flowing into compartment 53 from which it is delivered by conduit 55 to chamber 22 to supercharge the latter and thereby prevent undesirable arcing therein and failure of the ignition system at high altitudes. To provide circulation of air in chamber 22, bleeder holes 58 discharge air therefrom and said bleeder holes are arranged so as to create streams or currents of high pressure air around terminal 19, keeping the latter dry and preventing arcing therefrom.

A modified pump apparatus adapted for operation in the above-described magneto unit is shown in Figs. 4 to 6 and includes a cylindrical

housing 60 comprising end plates 60a and 60b and a cylindrical wall member 60c. Plates 60a and 60b and member 60c are rigidly secured in operative relation to each other by suitable means, such as bolts 61 (Fig. 6), radially projecting lugs 62 being formed on the parts of housing 60 for receiving said bolts. Annular gaskets 60d may be interposed between the ends of housing member 60c and plates 60a and 60b to render the connection therebetween fluid-tight. Housing 60 is eccentrically mounted on main rotor shaft 13, which extends through eccentrically disposed recesses in plates 60a and 60b, and said housing is resiliently held against angular movement by a plurality of tubular members 63 of resilient material, such as rubber. Each of members 63 is contained in a suitable indentation 63a in magneto housing 10 and is pressed between the walls of indentation and pump housing 60, the same being located so as to bear against one side of one of lugs 62 and resist yieldably any tendency of said pump housing to move angularly or radially. To positively prevent more than limited angular movement of housing 60, a pair of recesses 64 are provided in magneto housing 10 for freely receiving two of lugs 62, the walls of said recesses being adapted to rigidly resist rotation of housing 60 when said lugs move into engagement therewith.

Mounted in housing 60 for rotation with shaft 13 is a cylindrical pump rotor 65 which is concentric with said shaft and is keyed or otherwise secured thereto. A plurality of vanes or blades 66 are slidably mounted in radial slots 67 provided in said rotor and spaced equal angular distances around the periphery thereof, said vanes being centrifugally pressed into fluid-tight engagement with the inner wall of member 60c when said rotor is rotated. In order to lighten the latter, a plurality of axially extending recesses 68 may be drilled or otherwise provided in said rotor, said recesses preferably having their centers equal distances apart on a common circle concentric with the axis of rotation of said rotor. Said recesses may be fitted with oil soaked felt or the like and be connected with the periphery of the rotor through openings 68a plugged with porous bronze or the like to thereby lubricate the interior of the pump.

Peripheral compression chambers are thus defined by vanes 66, rotor 65 and housing 60, and air is admitted into said chambers during rotor operation through an arcuate inlet port 69 (Figs. 5 and 6) provided in plate 60a, which port opens into the space between said housing and wall 12. A recess 70 in the bottom wall of housing 10a connects said space with the exterior of magneto housing 10 and preferably has a suitable filter 71 mounted therein for removing foreign matter from the air admitted to said space. The air compressed in the compression chambers is discharged from the latter through a discharge port 72, 73 comprising an arcuate slot 72 on the inner face of plate 60a and an opening 73 of circular cross-section which connects said slot with the exterior of said plate. A suitable hose coupling member or connection 74 is secured in recess 73 and is adapted to mount one end of a flexible hose or tubing 75 which has the other end thereof connected to a second hose coupling 76, the latter being threadedly mounted in flange 22a to discharge air into distributor chamber 22. By virtue of this connection, the compressed air from pump 60, 65 is delivered to chamber 22 to supercharge the latter.

There is thus provided ignition apparatus having a novel arrangement of parts, including pumping means, whereby the interior of the housing of said apparatus may be supercharged. There is also provided novel pump means adapted to be operatively mounted in a magneto-generator for supercharging the distributor chamber of said generator, said pump means being mounted in a novel manner for cooperation with the main rotor shaft of said generator so as to operate without danger of binding and with a minimum loss of efficiency due to air leakage during compression. Novel means are embodied in the generator for directing air into the pump means and for delivering the pump discharge to any desired chamber or compartment of said generator. If desired, the magneto casing may be relatively air-tight and the pump may be used to supercharge the entire magneto and distributor casing. The pumping means are mounted in a novel manner so as to facilitate assembly of the parts thereof in operative position in the magneto and to permit efficient operation thereof with a minimum of wear. There is additionally provided a novel arrangement for supercharging the interior of a distributor chamber and for maintaining currents of supercharged air around connectors leading into said chamber, whereby the connectors are kept dry and the currents carried thereby are prevented from arcing.

Although only two embodiments of the invention have been illustrated and described, it is to be expressly understood that the same is not limited thereto. For example, it will now be apparent to those skilled in the art that the rotor of the embodiment of Figs. 1 to 3 may be lightened by having recesses drilled therethrough or that the vanes of the embodiment of Figs. 4 and 5 may have their outer edges blade-shaped. Moreover, adapter 48 of Figs. 1 to 3 may be integrally formed with housing section 10a. Various other changes may be made in the design and arrangement of the illustrated parts without departing from the spirit and scope of the invention. For a definition of the limits of the invention, reference will be had primarily to the appended claims.

What is claimed is:

1. In ignition apparatus having a housing including at least two sections and a drive shaft mounted in said housing, a pump for supercharging said housing, said pump comprising a rotor mounted on said drive shaft, centrifugally responsive vanes slidably mounted in said rotor, and a pump casing containing said rotor and cooperating with the latter and said vanes to define a plurality of pressure chambers, and adapter means adjoining said pump for admitting air to said pressure chambers and for delivering the compressed air from said chambers to a predetermined portion of said housing, said pump and adapter means being clamped in operative position between said housing sections.

2. In apparatus including a housing and a drive shaft in said housing, pump means for supercharging the interior of said housing comprising a pump casing supported by said shaft in eccentric relation thereto, a pump rotor concentrically mounted on said shaft for rotation therewith, and a plurality of centrifugally actuated vanes slidably mounted in said rotor for engagement with said casing, and means for securing said casing against rotation comprising lugs formed on said casing, indentations in said housing cooperating with said lugs to positively limit the angular

movement of said casing and members mounted in said housing to engage said casing and yieldably resist any angular movement of the latter.

3. In apparatus having a housing wherein a rotary shaft is mounted, a compartment formed in said housing, an air pump operated by and mounted on said shaft within said housing between spaced bearings for said shaft, and means connecting the inlet port of said pump to the housing exterior and the discharge port of said pump to said compartment.

4. In apparatus having a housing and a rotary shaft mounted in said housing, a chamber in said housing, a pump apparatus having a rotor mounted on said shaft intermediate the ends of the latter, and adaptor means mounted in said housing and adjoining said pump apparatus, said means forming chambers for admitting air to said pump apparatus from the housing exterior and for delivering the entire discharge of said pump apparatus to said first-named chamber.

5. In a magneto-generator having a housing wherein are mounted a main rotor shaft, a distributor and a connector for delivering high tension current to said distributor, a compartment for said distributor formed in said housing, said connector extending through the wall of said compartment and having a terminal on the exterior thereof, a pump mounted on said rotor shaft for supercharging said compartment, and at least one bleeder port in said compartment wall adjacent said connector for discharging air from said compartment in the vicinity of said connector terminal to maintain the latter dry and prevent arcing therefrom.

6. In a magneto-generator having a housing wherein are mounted a distributor, a magnetic rotor, a shaft for said rotor, a coil cooperating with said rotor and a conductor connecting the high tension winding of said coil to said distributor, a compartment for said distributor formed in said housing, said conductor extending through the wall of said compartment, a pump mounted on said rotor shaft, means for conducting the discharge of said pump to said compartment to supercharge the latter, and means comprising at least one vent passage in the wall of said compartment for discharging air therefrom, said vent passage being located to emit a stream of high pressure air from said compartment adjacent to the connection between said conductor and winding.

7. In a magneto-generator having a supercharged chamber and a conductor carrying current into said chamber from a terminal on the exterior of said chamber, a plurality of air bleeder passages formed in the chamber wall around said conductor so as to form currents of supercharged air on the exterior of said chamber adjacent to said conductor and the terminal therefor.

8. In ignition apparatus having a main rotor shaft, a distributor compartment, and means for delivering high tension current into said compartment including a connector on the exterior of the latter, a pump mounted on said rotor shaft for supercharging said compartment, and means comprising at least one vent passage in the wall of said compartment for discharging air therefrom, said vent passage being located to create a stream of high pressure air adjacent to said connector.

9. In apparatus of the class described, a rotatable shaft having an axially extending recess therein for containing lubricating oil, a stationary member having a bearing surface surround-

ing said shaft, said shaft having a radially extending passage extending from said recess to said bearing surface, and a porous metal element filling said passage.

10. In apparatus of the class described, means forming a substantially closed compartment, means for supplying a gaseous medium to said compartment at a pressure in excess of the surrounding atmosphere, means including a terminal for supplying electric current to a conductor inside said compartment, and means for discharging said gaseous medium from said compartment in the immediate vicinity of said terminal.

11. In apparatus of the class described, rotatable means having a recess therein for containing a lubricating medium, a passage in said rotatable means connecting said recess with the periphery of said means, and porous metallic means in said passage through which said lubricating medium may be driven by centrifugal force during rotation of said rotatable means.

12. In apparatus including a housing and a drive shaft mounted in said housing, means for supercharging the interior of said housing comprising a pump casing supported by said shaft in eccentric relation thereto, a pump rotor supported by said shaft within the casing, means to limit the angular movement of the casing when the rotor turns comprising resilient members located between said housing and said casing for resiliently resisting any such angular movement of the casing, and means connecting the high pressure side of the pump to the interior of the housing.

13. In apparatus of the class described a housing having a relatively fluid-tight compartment, a shaft, means in said housing for supporting said shaft, a rotary fluid pressure pump for supplying air under pressure to said compartment comprising a cylindrical casing eccentrically and irrevolubly disposed about said shaft and a rotor in said casing fixedly mounted on said shaft, and means to connect the high pressure part of the pump to the compartment.

14. In apparatus of the class described a housing, spaced bearings therein, a shaft journalled in said spaced bearings, pump means comprising a casing within which said shaft is adapted to rotate, and resilient means to limit the angular movement of the casing about the shaft.

15. In apparatus of the class described a housing, a shaft journalled therein, a pump casing mounted on said shaft in said housing, a rotor secured to said shaft within said casing, means for limiting axial movement of said casing on said shaft, and means for limiting angular movement of said casing relative to said housing.

16. In apparatus of the class described a housing having a relatively fluid-tight compartment, a shaft, two spaced bearings in said housing for supporting said shaft, and a rotary fluid pressure pump mounted between said bearings for supplying air under pressure to said compartment, said pump comprising a cylindrical casing eccentrically disposed about said shaft, means to limit the angular movement of said casing relative to said housing, a rotor operatively disposed in said casing and rigidly secured to said shaft, and means to conduct the fluid under pressure from the pump to the compartment.
